UNITED STATES PATENT OFFICE.

JOHN H. RESE, OF ALLEGHENY, PENNSYLVANIA.

MAGAZINE TORPEDO-CANE.

SPECIFICATION forming part of Letters Patent No. 732,587, dated June 30, 1903.

Application filed February 25, 1903. Serial No. 145,016. (No model.)

To all whom it may concern:

Be it known that I, JOHN H. RESE, a citizen of the United States, and a resident of Allegheny, in the county of Allegheny and State of Pennsylvania, have invented a new and Improved Magazine Torpedo-Cane, of which the following is a full, clear, and exact description.

My invention relates to certain novel and useful improvements in magazine-canies for exploding torpedoes or similar charges.

The invention is embodied in the construction, combination, and arrangement of parts as is described in this specification, delineated in the drawings, and set forth in the appended 15 claims.

Reference is to be had to the accompanying drawings, forming a part of this specification, in which similar characters of reference indicate corresponding parts in all the figures.

20 Figure 1 is a perspective view of a torpedo-cane embodying my invention. Fig. 2 is a central longitudinal vertical sectional view of the same, the exploding-plunger being shown in its lowermost position in the casing or chamber. Fig. 3 is a view similar to Fig. 2, the plunger being shown in contact with the exploding-wall of the chamber or casing. Fig. 25 4 is a transverse sectional view taken on the line 4-4 of Fig. 2, and Fig. 5 is a perspective 30 view of the band or clamping-ring employed for covering the inlet of the tubular cane portion of the device. Fig. 6 is a side view of the plunger.

Referring now to the drawings in detail, the 35 numeral 1 designates the tubular cane portion of the device, which may be of any suitable or desired character and is preferably provided with a handle or gripping portion, as at 2. As will be evident, this tubular cane 40 portion serves as a magazine for the torpedoes or caps, and at the lower end thereof is arranged the housing or casing 3, said casing having formed therein a longitudinal vertically-extending bore, as at 4, which is enlarged or widened at the lower end of the casing, as shown at 5. As will be seen, particularly upon reference to Figs. 2 and 3, a curved 45 passage-way, as at 6, leads from the tubular cane portion into the reduced or narrowed 50 portion of the bore in the casing, such curved passage-way serving as a means for conducting the explosive charges to the plunger. The

plunger, the construction of which is clearly illustrated in Figs. 2, 3, 6, forms an important feature of the present invention and comprises a lower or striking member 7, which is adapted to contact with the ground or other surface when the device is in use, and at the upper portion of this member 7 the plunger is enlarged or widened, as at 8, until it is approximately equal in diameter to the width of the enlarged portion of the bore, and from the enlarged portion 8 of said plunger there extends upwardly a member 9, adapted to slide within the narrow or reduced portion 4 55 of the bore and is provided with a recess or a cavity 10, which when the plunger has reached the limit of its travel upwardly in the casing registers or communicates with the curved 60 passage-way 6 and receives therefrom one of 5 of the torpedoes, as is clearly shown in Fig. 3.

On elevating or lifting the cane from the ground the plunger will, through force of gravity and its own weight, drop toward the bottom of the casing or housing 3 until the 75 shoulder 11 of the enlarged portion 8 abuts against a stop or limiting pin 12. The charge will then roll or drop from the downwardly-inclined seat 13 of the recess 10 and onto the similarly downwardly inclined seat portion 8c 70 14, formed at the top of the member 7, such charge being retained in position on said seat by the vertical wall 15 of the enlarged portion of the bore. The charge is then ready to be exploded, and as the cane is brought downward 85 into contact with the ground the plunger will be forced upwardly in the casing and the charge exploded between the upper wall 16 of the enlarged portion of the bore and the seat 14 of said plunger. After the explosion 90 of the charge the fumes or burned products will pass out or escape through irregularly-shaped ports or channels 17, formed adjacent to the aforesaid upper wall 16. It will be observed that this curved channel or duct is arranged at the top portion of the explosive-chamber, so that the burned or exhausted charge and the refuse matter usually accompanying the same is carried out quickly and rapidly, so that it in no way or measure interferes with the explosion of the following 95 charge.

For the purpose of preventing the flames or exploded products from passing back into

the magazine-chamber, and thereby tending to explode the torpedoes, I have provided a safety-tongue, as at 18, which is formed integral with and depends from the upper wall 5 16 of the enlarged bore on the casing 3. This tongue when the plunger is forced upward is adapted to enter a slot or groove 19, formed in the widened portion 8 of the plunger, and, as will be observed, all communication between the exploding-chamber of the casing and the magazine-chamber is closed or shut off by this arrangement.

The torpedoes may be inserted in the tube 1 through a side opening 20, which is normally closed by a spring clamping-band 21, provided with a runner (see Fig. 3) or cork stopper 22 (see Fig. 5) of sufficient size to fit tightly within and close the said opening. By this means a constant air-pressure may be 20 preserved in the magazine portion of the cane which will prevent the charges from rebounding or being disturbed therein when the cane is struck against the surface of the ground to explode a charge in the casing. In case such 25 side opening 20 is not employed the torpedoes may be inserted in tube 1 by removing the handle 2. (See Fig. 1.)

It is important that the plunger shall fit and play very loosely in the chamber in order 30 to prevent clogging in use.

From the above description, taken in connection with the accompanying drawings, the construction, operation, and advantages of my improved device will be readily apparent. It is to be noted in particular that 35 the inclined seat 13 of the cavity or recess within the upper member of the plunger obviates the possibility of the charge remaining in the cavity when the plunger is traveling downward and has passed the tongue 18, and such tongue also insures that the flames or burned charges shall not in any way disturb or affect the unexploded torpedoes within 40 the cane.

While I have herein shown and described 45 my preferred device, it will of course be apparent that there may be modifications and variations in certain respects without departing from the principle of my invention or 50 sacrificing any of the advantages thereof.

Having thus described my invention, I

claim as new and desire to secure by Letters Patent—

1. A device of the class described, comprising a magazine-tube, a casing at the end thereof, an explosion-chamber in said casing, a plunger which is independent of the casing and adapted to slide therein and has a vertical slot in its lower member adjacent to the seat for the charge to be exploded, a depending tongue formed in the casing and adapted to enter said slot when the plunger is moved upward, thereby closing communication between the explosion-chamber and the magazine, and an exhaust-passage leading from 65 said chamber.

2. The combination with a magazine-tube and a casing at the end thereof communicating with said tube, of a plunger moving vertically in said casing, said plunger having 70 a recess formed therein, the bottom wall of said recess being inclined, a groove or slot formed in the plunger adjacent to the inclined wall of the recess, and a vertical tongue formed in the casing, adapted to enter said groove when the plunger is moved 75 upwardly in said casing.

3. A device of the class described, comprising a magazine-tube having an opening in the side thereof for the insertion of the 80 explosive charges, means for closing the said opening, a casing at the end of said tube and communicating therewith, a plunger comprising two members or arms having a downwardly-inclined seat formed at the point of 85 juncture of said members, the uppermost of said members having a cavity therein to receive a charge from the magazine when the plunger is in its uppermost position, the lower wall of said cavity being downwardly 90 inclined, the construction being such that a charge will be exploded by the contact of the seat with the wall of the casing, and an exhaust-passage leading from the explosion-chamber.

In testimony whereof I have signed my name to this specification in the presence of two subscribing witnesses.

JOHN H. RESE.
